INVENTOR

UNITED STATES PATENT OFFICE.

HERMAN ZARAFU, OF BROOKLYN, NEW YORK, ASSIGNOR TO ELEVATOR SUPPLIES COMPANY, INC., OF HOBOKEN, NEW JERSEY, A CORPORATION OF NEW JERSEY.

ELEVATOR-CONTROL APPARATUS.

Application filed February 10, 1926. Serial No. 87,502.

This invention relates to control apparatus for elevators and particularly to elevators electrically controlled, whether such control is centered in the car or at the various landings along the hatchway in which the car travels.

An object of the invention is to provide safety interlocking means whereby (except in case of emergency, such as fire) the car 10 cannot be started away from any landing unless and until all hatchway doors are closed and mechanically locked in closed position; and furthermore to render it impossible to reopen, or even to unlock, any 15 hatchway door until the car reaches the landing where such door is located and stops.

A feature of the invention in this connection lies in the provision of a safety circuit which is broken immediately prior to the removal of the mechanical lock on the door 20 operating members; it being impossible to remove said lock until said safety circuit has been opened.

A further feature of this apparatus, in installations where the doors are power operated (as by fluid pressure, for example) lies in its provision of a certain sequence for all the necessary operations, namely the breaking of the control circuit, the removal 25 of the lock on the door operating members, and the application of the power (fluid pressure, for example) to the door; all three operations being effected by a single initial act on the part of the operator. I thereby 30 reduce the work of the operator to a minimum, assuring faster service for the passengers, but at the same time necessitating a safety sequence of operation which eliminates any 35 possibility of accident.

Heretofore it has been customary to have electric interlocks of such a nature that the control circuit for the elevator was broken as a consequence of the removal of the door lock or as a consequence of the door having 40 been opened to some extent. Many excellent and very serviceable types of interlocks operating in this manner have been constructed and patented, and have proven satisfactory from the commercial viewpoint. But they

do not provide an absolutely safe sequence 50 of operation, because with such interlocks the car's motive power is still in operating condition with respect to the car even after the door is put in an unsafe condition.

I believe I am the first to eliminate this 55 objection by providing a unitary apparatus which will permit the breaking of the circuit and the removal of the lock on the door operating members to be successive steps effected by a single initial actuation; but at 60 the same time will positively prevent the unlocking of the door unless and until the car is stopped with its control circuit broken.

Other objects and advantages to be derived from my invention will appear as the 65 description progresses, reference being had to the accompanying drawings, wherein Fig. 1 shows my apparatus as it appears at a hatchway landing, together with an actuating device on the car.

Fig. 2 shows some of the novel features of the apparatus of Fig. 1 on a larger scale.

Fig. 3 is a view at right angles to Fig. 2, showing some of the parts appearing in 70 Fig. 2.

Figure 4 is a view showing a modified 75 form of a portion of the apparatus.

In the drawing 1 designates a car adapted to travel in a hatch 2, and 3 designates a landing at which a sectional door 4 is located. Beneath the floor of the car, but attached thereto, is a cam 5 adapted in its extended position to engage roller 6 when the car is at the floor level. Roller 6 is mounted on an arm 32 pivotally secured to 80 casing 8 by means of shaft 33 journaled in bearing 7. Casing 8 is secured to the hatch framework in the proper location by means of bolts 9.

Extension of car cam 5 may be controlled 85 either automatically or manually in any manner well known in the art, such as shown in patents to Norton 1,545,164, 1,550,449 and 1,562,184, issued respectively on July 7, 1925, Aug. 18, 1925, and Nov. 17, 1925, 90 or as shown in patent to Fear 1,565,143, issued Dec. 8, 1925. Since the control of the car cam forms no part of my invention, I

have shown it controlled in a manner which is easy to illustrate and which serves the purpose as well as any other; but obviously I wish my Letters Patent to protect my ² novel apparatus regardless of the type of mechanism employed to actuate roller 6 when car 1 is opposite thereto.

10 designates a power cylinder of a type well known in the art for applying power ¹⁰ to the toggle arms 11 and 12 attached to door 4. Cylinder 10 is capable of causing the arms 11 and 12 to open door 4 when air pressure is admitted to the cylinder thru line 13, and of causing the arms to close the door ¹⁵ by action of a spring within the cylinder 10 when the air pressure is exhausted therefrom, as shown in patent to Weeks, No. 1,540,972 granted June 9, 1925. As explained in this Weeks patent, and as further explained in another patent to Weeks, No. 1,530,964 of March 24, 1925, a handle is mounted on the toggle arms 11 and 12 as shown in Fig. 1 to allow manual opening of the doors in case of failure or omission of ²⁰ air pressure.

Obviously other convenient types of door actuating mechanisms may be employed, the type just referred to being shown merely by way of illustration.

20 With this type of power cylinder admission and exhaust of air is controlled preferably by a valve indicated generally at 15 and located at the upper corner of casing 8 as shown best in Fig. 2. The valve contains a ²⁵ passage 16 connected with a suitable source of supply. Communication between this passage and line 13 is normally cut off by ball valve 17 resting on its seat. Beneath ball valve 17 is a stem 19.

40 When this stem 19 is raised in a manner presently to be described, valve 17 will lift from its seat, allowing air under pressure to pass from the source of supply thru passages 16, 20 and line 13 to cylinder 10. Upward movement of valve 17 will cause a corresponding upward movement of ball valve 22 to its upper seat 21^a thru the intermediary of plunger 22^a, thereby cutting off communication between line 13 and exhaust port 21.

50 When it is desired to close the door 4 again, valve stem 19 will resume its lower position (shown in Fig. 2) thru an operation to be described hereinafter. This will cause ball valve 17 to cut off communication with the source of supply, while ball valve 22 will resume its lower seat in response to the urge of spring 18, thereby uncovering exhaust port 21 and allowing the air in cylinder 10 ⁵⁵ to escape to the atmosphere by way of line 13 and port 21, in the manner indicated in Fig. 2.

60 Pivotedly suspended from toggle arm 11 is a rod or bar 23 to which is pivotally secured at its lower end a yoke 26 supporting

two vertical rods 27 and 28 (shown best in Fig. 3). These rods are connected by another cross-bar 29, which has an inclined upper surface 29^a over which arm 30 of rocker 31 is adapted to ride. Obviously when arm 30 is resting on surface 29^a no upward movement of rod 23 can take place, rocker 31 being secured on pivot 33 and held in locking position by spring 40. Furthermore in this condition toggle arm 11 is prevented from taking any upward movement, being held in the position shown in full lines in Fig. 1 by rod 23. Now since the toggle arms must travel upward in order to permit the door to open, it is apparent that in the position of ²⁰ rocker 31 shown in Fig. 2 the door 4 is locked in closed position.

Projecting from rocker 31 at a point near its pivot 33 is an arm 35 having a flat end 36 in which is inserted a pin 37 threaded ²⁵ secured at the other end in a thimble 38 pivoted at 39 to casing 8. On pin 37 is coiled spring 40 (above referred to) which normally urges rocker 31 into the position shown in Fig. 2.

90 To a flat serrated surface 41 on rocker 31 flange 45 is adjustably secured by means of screws 42 movable in slots 43. This flange is also serrated to correspond with surface 41. Integral with flange 45 is an arm 46, having at its end an insulated block 47 in which is mounted a roller 48 of conducting material, which roller is adapted to make contact between two resilient conducting blades 49 which are mounted in an insulated base 50 which is free to rock, to a certain extent, upon its support.

95 Each of the blades 49 has a terminal to which terminals are secured conductors 90 and 91, these conductors being part of the control circuit for the hoisting motor of elevator 1. These conductors are secured to terminal block 92, to which point will pass the conductors carrying the current which supplies the motor.

100 Thus it is seen that roller 48 is in effect a circuit maker and breaker for the car control circuit. In the position shown in Fig. 2 the circuit is made by the roller, and will be broken only when rocker 31 is made to pivot about bearing 7 in the manner presently to be described.

105 Pivoted to the upper wall of casing 8 is an intermediate valve actuator or bumper 55, having a lug 56 at its lower left-hand corner adapted to be contacted by knob 57 on the end of rocker 31, this knob being of rubber or other suitable material. Extending downwardly from bumper 55 is an arm ¹¹⁰ 58 having a slot 59 in which is inserted a pin 60 riveted or otherwise fixed to casing 8 at 62. The central portion of bumper 55 is drilled through, but the upper end of the drilled hole is of smaller diameter than the lower. The lower end is tapped for the in- ¹¹⁵

section of a threaded plug 52, which serves as a retainer for spring 60, which spring bears against plunger 61 holding the shoulder of the plunger against seat 62. The force exerted by spring 60 may be adjusted by means of plug 52, also by means of nut 64 threaded to pin 60, which nut affords a means of raising or lowering bumper 55 about its pivot 65. Nut 64 also serves to position the bumper in striking relation to valve stem 19.

The various parts of the apparatus having been described, a complete operation will now be followed through. Let us suppose that the operator of car 1 has stopped at landing 3, and wishes to open the door 4. He depresses pedal 70 against spring 71, causing cam 5 to be extended to engage roller 6, pushing the latter to the left, thereby rotating the rocker 31 about its pivot, and causing arm 30 to ride out over the upper surface 29^a of cross-bar 29.

Before arm 30 entirely clears bar 29, however, arm 46 will have withdrawn roller 48 from contact with resilient blades 49, thereby opening the circuit to the hoisting motor at that point, and preventing any possible movement of the car by its hoisting motor.

After clearing cross-bar 29, knob 57 on the end of the rocker will engage lug 56 of bumper 55 to turn the same about its pivot 65, causing plunger 61 to raise valve stem 19 to admit air to the cylinder 10 to raise the toggle arms (rod 23 now being free to follow toggle arm 11 in its upward movement). Raising of the toggle arms causes door 4 to slide to open position in the usual manner, as is obvious from an inspection of Fig. 1.

When the operator wishes to close (and lock) door 4 again preparatory to starting away from the landing 3, he will remove his pressure from pedal 70 allowing spring 71 to retract cam 5. Retraction of cam 5 will permit spring 40 to initiate the return of rocker 31 to its left hand position. The rocker cannot yet return the full distance, however, due to the fact that cross-bar 29 is in its upper position, hence in the path of finger 72. But it can, and does, return far enough to render bumper 55 free to swing back to the position shown in Fig. 2 under the influence of gravity and the downward movement of valve stem 19: the downward movement of said valve stem being brought about by the aid of spring 18.

Exhaust now takes place from cylinder 10 thru line 13 and exhaust port 21, so that the spring above the piston in cylinder 10 forces the toggle arms back to the position shown in full lines in Fig. 1, thereby closing the door.

The downward movement of the toggle arms causes the descent of rod 23 and cross-

bar 29, so that the latter rides down out of the path of finger 72, which thereby becomes free to continue its movement to the extreme left-hand locking position, (shown in Fig. 2) under the influence of spring 40. Finger 72 and arm 30 again rest on surface 29^a, and the door is again locked in closed position.

Furthermore this final movement of rocker 31 to the left causes the return of roller 48 between the spring blades, so that the circuit to the hoisting motor is remade, and the power can be applied for moving the car (provided, of course, all other connections are made, and all other landing doors are closed).

Thus it is apparent that the most desirable sequence of operation is obtained by my novel apparatus not only on the opening movement, but also on the closing movement of the doors.

I have described and illustrated my invention in its more common aspect, namely as applied to pneumatically actuated elevator doors, but obviously the principle and the inventive features of the apparatus can be applied in numerous other ways which will occur to those skilled in the art. For example, where the doors are electrically opened or closed, by means of a suitable electric or electro-magnetic device such as that illustrated in Fig. 4, which is taken from the disclosure in patent to Watson No. 790,334 of May 23, 1905, rocker 31 instead of operating a valve, will operate a circuit making device for the door operating motor; as for example, the spring influenced contact maker 102 shown in Fig. 4 in which event the valve 15 and bumper 55 may be dispensed with. The valve and bumper may also be dispensed with, of course, whenever the fluid pressure operation is dispensed with.

From an inspection of Figures 1 and 4 it will be apparent that whenever the operator retracts cam 5, allowing rocker 31 to return, spring 104 will return electric contact 102 to circuit open position, substantially as in the patent to Watson, above referred to, thereby releasing the tension on chain 103, so that the door closer cylinder 10 may function to close the door. If for any reason the motor 101 fails to function properly the door 4 may be opened manually by means of the handle provided on toggle arm 12 just as in the case of a failure of air pressure when the construction shown in Figures 1 to 3 is employed; it being understood that the construction of the door closer cylinder 10 remains as described heretofore. In other words, I may employ any one of three different methods of opening the door 4 (namely, fluid pressure, electricity, or hand power) but with each method I prefer to retain the same door-closing

means; principally because this means has proven simple and effective, but also because such a construction is particularly well suited for use with my novel interlocking apparatus.

I, therefore, do not limit myself to the specific embodiment, construction, or arrangement of parts herein described and illustrated, but only by the scope of the invention as disclosed herein and as defined in the appended claims:

I claim:

1. In an elevator control apparatus, a door, a car relatively movable with respect to the door, toggle arms pivotally connected and adapted in normal position to lock the door against movement, a lock connected to one of said arms, means for releasing said lock, power means operatively associated with said toggle arms for controlling the movement of said door, said means being dependent in its operation upon the previous release of said lock.

2. In an elevator control apparatus, a door, a car relatively movable with respect to the door, toggle arms pivotally connected and adapted in normal position to lock the door against movement, a lock connected to one of said arms, a power controlling switch, and a single operating member for said lock and switch for causing, first, the opening of said switch, and, subsequently thereto, the release of said lock, whereby the power control for said car is rendered inoperative before the lock is removed from the toggle arms.

3. In an elevator control apparatus in combination, a door, a car relatively movable with respect to the door, means for opening the door comprising an actuating mechanism, a lock engaging said actuating mechanism, a power controlling switch, and a single operating member for said lock and switch for causing first, the opening of said switch, and, subsequently thereto, the release of said lock, whereby the power control for said car is rendered inoperative before the lock is removed from the door.

4. In an elevator control apparatus, a door, a car relatively movable with respect to the door, fluid pressure means for opening the door, a lock for the door, a power controlling switch, and operating mechanism for said lock, switch and fluid pressure means, constructed and arranged to cause first, the opening of said switch, and subsequently thereto, the release of said lock and the operation of said fluid pressure means.

5. In an elevator control apparatus, a door, a car relatively movable with respect to the door, means for opening the door comprising a fluid pressure motor, a valve for controlling the supply of fluid to said

motor, a power controlling switch, and operating mechanism for said switch and valve constructed and arranged to complete, first, the opening of said switch and, subsequently thereto, the operation of said valve, whereby the door can be opened only after said switch is opened.

6. In an elevator control apparatus, a door, a car relatively movable with respect to the door, means for opening the door comprising a fluid pressure motor, a power controlling switch, and an operating connection constructed and arranged to complete, first, the opening of said switch and, subsequently thereto, the operation of said motor, whereby the door can be opened only after said switch is opened.

7. In an elevator control apparatus, a door, a car relatively movable with respect to the door, means for opening the door comprising a fluid pressure motor and operating connections from said motor to the door, a valve for said motor, a car controlling switch, and operating mechanism for said valve and switch constructed and arranged to complete, first, the opening of said switch and, subsequently thereto, the operation of said valve, whereby the door can be opened only after said switch is opened.

8. In an elevator control apparatus, a door, a car relatively movable with respect to the door, toggle arms pivotally connected and adapted in normal position to lock the door against movement, power means associated with said toggle arms for controlling the movement of said door, a power controlling switch, and operating mechanism for said switch and power means constructed and arranged to cause, first, the opening of said switch and, subsequently thereto, the operation of said power means.

9. In an elevator control apparatus the combination with a door, of a car relatively movable with respect to the door, a circuit to the hoisting motor for said car, a switch in said circuit, toggle arms associated with said door to cause movement thereof, a motor for controlling the movement of said toggle arms, and an operating connection for said switch and motor constructed and arranged to cause, first, the opening of said switch, and subsequently thereto, the operation of said motor.

10. In an elevator control apparatus the combination with a door, of a car relatively movable with respect to the door, a circuit to the hoisting motor for said car, a switch in said circuit, toggle arms pivotally connected and adapted in normal position to lock the door against movement, a lock connected to one of said arms adapted to lock the toggle system, and operating mechanism for said switch and lock constructed and arranged to cause first, the opening of said switch, and, subsequently

thereto, the removal of said lock, whereby the door remains locked until after said circuit is broken.

11. In an elevator control apparatus the combination with a door, of a car relatively movable with respect to the door, a circuit to the hoisting motor for said car, a switch in said circuit, toggle arms pivotally connected and adapted in normal position to lock the door against movement; a lock on one of said arms adapted to lock the toggle system, a motor for controlling the operation of said toggle arms, and a unitary operating mechanism for said switch, lock and motor.

12. As a sub-combination, a door, a car relatively movable with respect to said door, toggle arms pivotally connected to the door, a rod depending vertically from one of said arms, a detent engaging said rod and preventing movement of said arms from normal position, and means on the car for releasing said detent.

13. As a sub-combination, a door, a car relatively movable with respect to said door, toggle arms pivotally connected to the door, a rod depending vertically from one of said arms, a detent engaging said rod and preventing movement of said arms from normal position, a circuit to the hoisting motor for the car, a circuit closer therefor, and a single operating member for said detent and circuit closer.

14. As a sub-combination, a door, a car relatively movable with respect to said door, toggle arms pivotally connected to the door, a rod depending vertically from one of said arms, a detent engaging said rod and preventing movement of said arms from normal position, a spring normally insuring engagement of said detent with said rod, and means on the car for releasing said detent against the inclination of said spring.

15. An interlocking system for an ele-

vator comprising a door actuating mechanism, a rod depending vertically from said door actuating mechanism, a yoke on the lower end of said rod, a transversely movable member on the car, a rocker arm pivotally mounted in position to be engaged by said member, a projection on said rocker arm normally engaging said yoke, thereby locking said actuating mechanism, and circuit closing means operatively connected to said rocker arm.

16. An interlocking system for an elevator comprising a door actuating mechanism, a rod depending vertically from said door actuating mechanism, a yoke on the lower end of said rod, a transversely movable member on the car, a rocker arm pivotally mounted in position to be engaged by said member, a projection on said rocker arm normally engaging said yoke, thereby locking said actuating mechanism, circuit closing means operatively connected to said rocker arm, and a power controlling member for said actuating mechanism positioned so as to be engaged by said rocker arm when moved from its normal position.

17. An interlocking system for an elevator comprising a door actuating mechanism, a rod depending vertically from said door actuating mechanism, a yoke on the lower end of said rod, a transversely movable member on the car, a rocker arm pivotally mounted in position to be engaged by said member, a projection on said rocker arm normally engaging said yoke, thereby locking said actuating mechanism, circuit closing means operatively connected to said rocker arm, and a valve for controlling the admission of pressure fluid to said actuating mechanism positioned so as to be engaged by said rocker arm when moved from its normal position.

Hoboken, N. J., 2/5/26.

HERMAN ZARAFU.
